UNITED STATES PATENT OFFICE.

JOHN B. HADAWAY, OF BROCKTON, MASSACHUSETTS.

LIP-TURNING MACHINE.

SPECIFICATION forming part of Letters Patent No. 638,010, dated November 28, 1899.

Application filed October 14, 1897. Serial No. 655,194. (No model.)

To all whom it may concern:

Be it known that I, JOHN B. HADAWAY, a citizen of the United States, residing at Brockton, in the county of Plymouth and State of Massachusetts, have invented certain new and useful Improvements in Lip-Turning Machines; and I do hereby declare the following to be a full, clear, and exact description of the invention, such as will enable others skilled in the art to which it appertains to make and use the same.

The present invention relates to sole-machines, and more particularly to a machine for turning up and setting the "lip" of a lipped insole, such machines being generally known in the art as "lip-turning" machines.

The present invention has for its object to produce a machine of this character which will expeditiously turn up and set the lip, im- 20 parting thereto the desired angular set relatively to the surface of the sole and arranged to act upon the lip in such manner that the fibers of the leather of which the lip is composed, and more particularly at the angle be- 25 tween the lip and feather, will be pounded and compacted, whereby said lip will retain the angular position to which it has been set relatively to the surface of the sole.

The present invention therefore consists of 30 the lip-turning machine which will be hereinafter described, and particularly pointed out in the claims.

The present invention is illustrated in the accompanying drawings, in which—

35 Figure 1 represents the machine in side elevation with the driving-pulley removed. Fig. 2 represents a top plan view of the machine. Fig. 3 represents a rear elevation of portions of the fixed frame, the driving-shaft, and the 40 main actuating-lever. Fig. 4 represents a broken plan view of the front part of the machine, showing the relative positions of the work-table and gage and the plow and lip-setting tool. Figs. 5 and 6 show a modified form 45 of plow or lip-turner. Fig. 7 represents a vertical sectional view, somewhat enlarged, showing the construction of the work-support.

Similar letters of reference designate corresponding parts throughout the several views.

50 In the drawings, A represents a supporting-frame of suitable size and shape to support the working parts, which may conveniently

be provided with legs or standards a, which rest upon a bench or other support in convenient reach of the operator. Upon the top of the frame A are the upwardly-projecting standards a', which may be secured thereto or cast integrally therewith, said standards a' being provided with suitable bearings a³ for the driving-shaft B. Upon one end of the driving-shaft B is a driving-pulley b and a suitable clutch b', whereby said shaft may be rotated to actuate the moving parts of the machine and its rotation controlled by the operator.

C represents a rotating work-support which is carried at the upper end of a short shaft c, which is mounted in a bearing c', carried by an elbow c², extending from the tubular bearing c³, which is affixed to the front of the machine in any suitable manner, as by the bolt c⁴. The shaft c extends into the tubular bearing c³, as shown in Fig. 7 of the drawings, and it is connected, by means of the headed screw c⁵⁰, with a rod c⁶, which rod is provided with a hook or other suitable means whereby it may be connected with a foot-treadle (not shown) to depress the work-support C. The work-support C is normally held elevated by means of a coiled spring c⁵¹, surrounding the rod c⁶ 80 within the tubular bearing c³. Splined to the shaft c is a gear c⁵, by means of which rotary movement may be imparted to the shaft c and the work-support C.

D represents a feed-wheel which is mounted 85 upon the end of an inclined shaft d, which rotates in a bearing d', formed upon an arm d², which is projected from a yoke d³, which extends forwardly from the standards a', the feed-wheel D being at such an inclination relatively to the work-support C that when the insole is superimposed upon the top of the work-support the feed-wheel D will fit into the angle between the lip and feather and bear upon the feather, which will be forced up by 95 the upward movement of the work-support C against the under side of the feed-wheel D.

The work-support C and the feed-wheel D are rotated in opposite directions by a worm b³ upon the main shaft B, which meshes with a worm-gear b⁴ upon the inclined shaft d, and shaft d carries a bevel-gear d⁴, which meshes with the bevel-gear c⁵, which is splined to the work-support shaft c. It will thus be seen

that a rotation of the main shaft B will, by means of the worm b^3 , worm-gear b^4 , and bevel-gears d^4 and c^5 , impart a simultaneous rotation to the feed-wheel D and work-support C 5 in opposite directions to feed the work along the lip turning and setting tools to bring successive portions of the lip of the insoles under the action of said tools.

If desired, the upper surface of the work-support C and the underside of the feed-wheel D may be roughened or serrated to insure a better hold upon the work and a more positive feeding thereof.

E represents a plow or lip-turning tool 15 which, as shown in Figs. 1, 2, and 4, consists of a forwardly-projecting curved finger carried by a bracket e, which is mounted upon some fixed portion of the machine-frame, as by a set-screw e', passing through a slot e^2 20 into the bearing d^1 . The plow E is curved to conform to and is adjusted to closely approximate the periphery of the feed-wheel D, so that it will enter between the lip and feather of the insole, and as said insole is fed along 25 between the feed-wheel D and work-support C the plow E will turn up the lip to be acted upon by the lip-setting tool. It will be observed that the plow E and the feed-wheel D act in the angle between the lip and feather 30 and gage and position the insole as it is fed along relatively to the lip-setting tool.

F represents the lip-setting tool, which as the sole is fed along acts to impart the proper set to the lip of the sole or to fix it in the position to which it has been raised by the plow E. For this purpose the lip-setting tool F is arranged to impart to the fibers of the lip, and more particularly to the base of said lip, short, sharp, and quick blows delivered in rapid 40 succession, whereby the fibers of the lip are compacted and the lip made to retain the desired position to which it has been placed relatively to the surface of the sole. To secure the above-suggested result in the machine of 45 the drawings, the lip-setting tool F is arranged to be reciprocated toward and from the edge of the sole upon the work-support, and preferably in an inclined direction, so that the tool F may act upon the lip at its base. For 50 this purpose the lip-setting tool F is mounted upon the end of a slide f, which is arranged to reciprocate in an inclined guideway f^1 , formed upon the yoke d^3 , said guideway being so inclined that the plane of reciprocation of the 55 slide f and the lip-setting tool F will be substantially parallel to the upper surface of the feed-wheel D. The slide f is held in position in the guideway f^1 by a plate f^2 , which is secured to said guideway f^1 in any suitable manner, as by the screws f^3 . The reciprocations of the slide f, carrying the lip-setting tool F, may be imparted thereto by any suitable mechanism, such as a link f^4 , which is pivotally connected to said slide f at f^5 and which 60 at its other end is pivotally connected to one end of a shaft f^6 in the upper end f^7 of a lever f^8 , which is fulcrumed at f^9 upon a shaft f^{10} ,

said shaft f^{10} being mounted in bearings a^4 in the ends of upwardly-projecting extensions a^5 of the standards a^1 . The lower end f^{11} of the lever f^8 is forked and engages an eccentric b^5 upon the main shaft B. The above-described arrangement is such that a rotation of shaft B will, by means of the eccentric b^5 , oscillate the lever f^8 upon its fulcrum f^{10} and by means of the link f^4 impart a reciprocation to the slide f and the lip-setting tool F, carried thereby, causing said tool to act upon the lip and impart thereto the desired set. The lip-setting tool F is preferably shaped as shown in the drawings, having a working end which is angularly disposed relatively to the shank, and is removably secured to the slide f by a screw s, which passes through a slot s^1 , formed in said shank, 85 whereby said tool F may be adjusted longitudinally upon the slide f. The working face of the tool F may be shaped as shown, having a substantially straight vertical face to cause the lip to be set vertically at a substantial 90 right angle to the surface of the sole, or the working end of said tool may be shaped to lay over and turn down the lip in a plane substantially parallel with the face of the insole, and in practice it is the intention to provide 95 a number of lip-setting tools having various shapes of working face suitable to position the lip in any manner desired for particular work.

While the machine as hereinbefore described constitutes a practicable and operative lip-turning machine which will turn up and set the lip of the sole in the desired position relatively to the surface of the sole, the thrust of the lip-setting tool against the sole 100 would have a tendency to push the sole off of the work-support, and said sole must be constantly held against the lip-turner E and the feed-wheel D with some force by the operator.

In order to hold the insole in position upon 105 the work-support C and to withstand the thrust of the lip-setting tool F against the lip of the insole, the machine of the drawings is preferably provided with a presser-foot H, which is arranged to grip the insole within 110 the lip and force the same down against the surface of the work-support C, thus clamping the same at the time the lip-setting tool 115 comes into contact with the lip. The presser-foot H is formed upon the lower end of a rod 120 or stem h, which is mounted loosely in a vertical bearing h^1 and prevented from turning therein by any suitable means, such as a pin h^2 , engaging a slot h^3 in said bearing. The presser-foot H is arranged to be moved toward 125 and from the surface of the work-support C to alternately clamp and release the sole thereon, and such movement may conveniently be secured by the following mechanism: The bearing h^1 is secured to the forwardly-extending arm h^4 of a three-armed lever h^5 , the lower arm h^6 of which is forked or yoke shaped and fulcrumed loosely upon a shaft h^7 , mounted 130 in a bearing carried by the yoke d^3 of the fixed

frame, the other arm h^8 of the three-armed lever h^5 being pivotally connected by a stud h^9 to a link h^{10} , which in turn is pivotally connected to one end of the rod f^6 , carried by the lever f^8 , the other end of the rod f^6 being connected to the link f^4 , which actuates the slide f and lip-setting tool, as before described. It will thus be seen that the presser-foot H and the lip-setting tool F are actuated by connected mechanism and move at substantially the same time toward and from the sole upon the work-support C . The presser-foot H is so positioned that its lower end engages and clamps the work just before the lip-setting tool F acts upon the lip, so that when said tool delivers its blow upon the lip the sole will be firmly held by the presser-foot H . The presser-foot is arranged to yield vertically in its bearing h' to accommodate inequalities in the thickness of the insole and for different thicknesses of insoles and at its upper end is acted upon by a spring h^{11} , which has a slot h^{12} , which engages a head h^{13} , formed upon a screw h^{14} , which is tapped into a threaded bearing h in the end of the stem h , and the opposite end of the spring h^{11} is secured by a screw h^{15} to a boss h^{16} , formed on the three-armed lever h^5 .

In order to provide for a horizontal adjustment of the presser-foot H toward and from the lip-setting tool F to provide for different thicknesses of lips, the bearing h' is provided with a bracket h^{17} , having a slot h^{18} , through which passes a set-screw h^{19} , by means of which the bearing h' is adjustably secured to the arm h^4 of the lever h^5 . By loosening the set-screw h^{19} the bracket h^{17} may be moved in and out upon the arm h^4 , thus moving the bearing h' and the presser-foot H , the slot h^{12} in the spring h^{11} permitting a movement of the head h^{13} of the screw h^{14} during such adjustment. By lifting the spring h^{11} and turning the screw h^{14} the tension of the spring h^{11} may be adjusted.

In order to accurately adjust the relative times of contact of the presser-foot H and the lip-setting tool F with the work to secure the best results, the stud h^9 , which connects the arm h^8 with the link h^{10} , is an eccentric stud, as shown in dotted lines, Fig. 1, which may be turned to secure the desired adjustment, as will be obvious from an inspection of the drawings.

It is of course to be understood that a constant rotation is imparted to the feed-wheel D and work-support C to feed the insole, and in order that the contact of the presser-foot H with the insole and the clamping action exerted thereon during the instant that the presser-foot is in contact with the insole may not retard the feeding movement thereof the presser-foot H is arranged to have a slight lateral movement with the sole, which is provided for by mounting the lever h^5 loosely upon the shaft h^7 and providing for a slight lateral play of said lever upon said shaft and also providing for a lateral movement of the arm h^8 of said lever upon the stud h^9 .

(See Figs. 2 and 4.) A spring m , secured at one end to a stud m' upon a fixed portion of the frame and at its opposite end to a stud m^2 , projected from one arm or member of the yoked end h^6 of the lever h^5 , acts to hold said lever h^5 and presser-foot H in their normal position and to return them to such position from the position to which they may have been moved by the contact of the presser-foot H with the insole.

In practice the end of the presser-foot H may engage and clamp the inner sole at a point in line with the line of movement of the lip-setting tool F , and thus form an abutment against which said lip-setting tool F may press the lip, or said presser-foot H may be set slightly to one side of the line of movement of the lip-setting tool and act merely to clamp the insole against the work-support during the action of the lip-setting tool thereon. In either case the presser-foot is found to be a desirable feature of the machine, inasmuch as it relieves the operator of the strain necessary to hold the insole in position against the pounding action of the lip-setting tool.

In the operation of the machine the insole, which has been previously cut or slit around its edge, is placed in position upon the work-support C with the lip-turner E and the edge of the feed-wheel D inserted in the slit, the upper flap formed by said slit being the lip of the insole, resting against the lip-turner or plow, and the under flap forming the "feather" of such insole, resting beneath the feed-wheel and lip-turner or plow, the work-support rising under the action of its spring and causing the feather of the insole to be gripped between the upper surface of the work-support and the feed-wheel. A rotation of the main shaft B now causes a rotation of the work-support and feed-wheel and feeds the insole, causing the plow or lip-turner to turn up or raise the lip, which is acted upon and given a series of rapid blows by the lip-setting tool to set or shape the same, as has been fully described.

Instead of forming the lip-turner or plow as shown in Figs. 1, 2, and 4 it may be constructed as shown in Figs. 5 and 6, wherein k shows the bracket and k' the lip-turner or plow, which upon its under surface has a cut-away portion k^2 , forming a flange k^3 to overlie a portion of the periphery of the feed-wheel D , the upper surface of the plow k' being rounded and beveled off at k^4 , as shown in the shaded lines of Fig. 6, whereby said plow will cause the lip of the insole to be gradually raised and turned up for the action of the lip-setting tool thereon.

Having fully described the construction and operation of my invention, I claim as new and desire to protect by Letters Patent of the United States—

1. In a lip-turning machine, the combination with a reciprocating lip-setting tool, of means to so actuate said tool and to support the work so as to cause said tool to strike

- and act upon the lip at the base thereof within the angle formed by the lip and feather of the insole, substantially as described. 45
2. In a lip-turning machine, the combination with a work-support, of a reciprocating lip-setting tool movable in a plane inclined to the surface of the work-support, substantially as described. 50
3. In a lip-turning machine, the combination with a reciprocating lip-setting tool, of clamping means arranged to hold the insole against the action of said tool, substantially as described. 55
4. In a lip-turning machine, the combination with a reciprocating lip-setting tool, of a presser-foot arranged to hold the insole during the operation of said tool, substantially as described. 60
5. In a lip-turning machine, the combination with a reciprocating lip-setting tool, of a work-support and means to clamp the insole against said work-support during the operation of said tool, substantially as described. 65
- 25 6. In a lip-turning machine, the combination with a reciprocating lip-setting tool of a clamping device and connected mechanism for actuating said tool and clamping device, substantially as described. 70
- 30 7. In a lip-turning machine, the combination with a reciprocating lip-setting tool, of a clamping presser-foot and connected mechanism for actuating said tool and foot, substantially as described. 75
- 35 8. In a lip-turning machine, the combination with a reciprocating lip-setting tool, of a clamping presser-foot and means for simultaneously actuating said tool and presser-foot, substantially as described. 80
- 40 9. In a lip-turning machine, the combination with lip-turning mechanism, of a rotating work-support and means to actuate the same, a clamping presser-foot arranged to clamp the work against said work-support, 70
- and means to permit a limited lateral movement of the presser-foot, substantially as described. 45
10. In a lip-turning machine, the combination with lip-turning mechanism, of a rotating work-support and means to actuate the same, a clamping presser-foot, means to permit a limited lateral movement of said presser-foot, and a spring to return said presser-foot, substantially as described. 50
11. In a lip-turning machine, the combination with a lip-setting tool and means to reciprocate said tool, of a presser-foot, and means to reciprocate said presser-foot, said tool and presser-foot movable at an angle toward and from each other and means to adjust the relative positions of the tool and presser-foot, substantially as described. 55
12. In a lip-turning machine, the combination with a work-support, of a feed-wheel inclined relatively to said work-support arranged to engage the angle between the lip and feather of the insole and a lip-setting tool movable in a plane parallel to the feed-wheel and arranged to act upon the lip at the base thereof, substantially as described. 60
13. In a lip-turning machine, the combination with a lip-turning device, and a lip-setting device, of a clamping device and actuating mechanism therefor arranged to alternately clamp and release the work, substantially as described. 65
14. In a lip-turning machine, the combination with a reciprocating lip-setting tool, of clamping means engaging the sole-surface within the lip to hold the sole against the action of said tool, substantially as described. 70

In testimony whereof I affix my signature in presence of two witnesses.

JOHN B. HADAWAY.
